EDWARD E. STEWART, OF WICHITA FALLS, TEXAS

APPARATUS FOR TREATING HYDROCARBON OILS

Application filed November 6, 1926. Serial No. 146,671.

My invention relates to apparatus for treating hydrocarbon oils for the purpose of separating and extracting the lighter from the heavier hydrocarbons by effecting separation of natural gasolines without injury to their texture, and/or for recovering additional gasoline by breaking down or cracking of the heavier hydrocarbons, the principal object of the invention being to provide an apparatus of this character wherein oils of different gravity and gasoline content may be treated according to their nature and in a manner to produce a maximum yield of gasoline.

Primarily the apparatus comprises skimming and cracking elements capable of operation independently of each other or in combination according to the grade of oil under treatment and the amount of gasoline which it is desired to recover.

More specifically, the apparatus comprises a recirculation circuit wherein the fluid is re-heated, recirculated, cooled at atmospheric pressure and reheated under pressure, the apparatus further providing for elimination of water vapors at substantially atmospheric pressure, thereby minimizing possibility of explosions in the still, by excluding such vapors from the cracking zone.

It is an established fact that light gravity liquids, such as kerosene, light distillates and gasoline, contain more hydrogen than the heavier oils. It is also a well known fact that when certain sufficient hydrogen is present in the cracking chamber that less coke is formed, and when charging stock that has been cracked is used and when the hydrogen is deficient an excess amount of coke is deposited. It is an object of my invention to provide an apparatus wherein the objectionable coking effects may be obviated by providing for a suitable amount of hydrogen in proportion to the other components.

Other advantages of the apparatus will be disclosed in the following description of the construction and operation of the mechanical elements of which the apparatus is composed.

In accomplishing the above and other objects of the invention I have provided im-

proved details of structure, the preferred forms of which are illustrated in the accompanying drawings, wherein—

Fig. 1 is a diagrammatic view of an oil refining and treating apparatus embodying my invention, some of the parts being broken away for better illustration.

Fig. 2 is an enlarged, longitudinal, sectional view of the bubble tower, wherein the initial separation of vapors is effected.

Fig. 3 is an enlarged vertical section of the primary separator tower.

Fig. 4 is an enlarged vertical section of a part of one of the bubble plates in the bubble and separator towers.

Fig. 5 is an enlarged detail perspective view of part of one of the elements of the bubble plate, a part of the hood being broken away.

Referring more in detail to the drawings:

1 designates an ordinary storage tank constituting a source of supply of oil to be treated. Leading from the tank 1 is a line 2 whereby oil is drawn from the supply by a pump 3 and delivered under pressure into a charging still 4. The oil is heated in the still 4 to a temperature of about 500 degrees F. and forced through a line 5 and branch 6 into the upper portion of a vaporizer or blending zone illustrated as a bubble tower 7, where it is delivered downwardly as a shower through a nozzle 8. The branch 6 carries a valve 9 for a purpose presently described.

When the apparatus is in operation and the vaporizer being supplied from the cracking still, as presently described, cracked vapors released in the vaporizer rise through the shower of liquid and, absorbing the lighter elements of the oil along with the water vapors, pass off from the top through a vapor line 10 to the primary separator tower 11, entering near the bottom of the tower. When the apparatus is in operation, cracked vapors enter the bottom and straight run vapors and liquid enter at the top of the vaporizer, forming a counter current of vapors and liquid, the cracked vapors rising through a liquid shower, a spreading element and bubble plates, effecting absorption or commingling of the lighter with the heavier hydrocarbons,

so that a large portion of the non-condensable vapors which are ordinarily lost are absorbed and carried over with the recovered vapors.

After passing through tower 11 the lighter vapors and non-condensable gases pass off through a vapor line 12, leading from the top of tower 11 to the bottom of a fractionating tower 13, the vapors passing through the fractionating tower being drawn off through a vapor line 14 into the condenser 15 and eventually into tank 16.

While the lighter components of the oil are passing to the condenser as described, heavier components collect as liquid in the bottom 15 of the vaporizer and primary separator towers, the liquid from the vaporizer passing to the bottom of the separator through a back trap line 17, level of the liquid in the separator being normally as indicated in the drawings.

When the apparatus is employed for cracking, liquid is drawn from the bottom of the primary separator tower through a suction line 18, preferably by means of a hot oil pump 19, and forced through the line 20 to a second hot oil pump 21, which forces the oil through a cracking still 22, wherein the oil is heated to a temperature of approximately 890 degrees F. and wherein a pressure of approximately 250 to 300 pounds is maintained. The force from the pump 21 carries the oil through the still and out through a transfer line 23 and a depending terminal 24 into the bottom of a cracking tower 25, the terminal 30 24 being provided with a hand valve 27. The tower 25 is provided with a number of pet cocks 25' spaced vertically for the purpose of determining levels of contents of the tower. Oil entering the first cracking tower as liquid 35 rises through the tower to an outlet line 28 at or near the top of the tower, through which the liquid is conducted to near the top of a second high pressure cracking tower 29, also provided with pet cocks 29' as and for the purpose specified in connection with the first cracking tower.

The oil passes through the second cracking tower 29 in the form of vapor to a pressure relief line 30, opening to the tower near its lower end, through which the vapors are conducted to near the bottom of a secondary separator tower 31. The line 30 carries a hand valve 32. An emergency connection between the second cracking tower and the secondary 50 separator tower is provided in the line 33, which leaves the tower 29 and enters the tower 31 at elevations above the line 30, the emergency line being also provided with a hand valve 34. The vapors entering the secondary 55 separator tower expand, releasing the pressure in the circuit, the cracked components passing off from the top of the secondary separator through a vapor line 35 into the lower portion of the vaporizer 7, through which 60 they rise, coming in contact with the initial

charging vapors and oils or water vapors, as heretofore described. The heavier components (fuel oil) are drawn off from the bottom of the secondary separator tower through a tar line 36 and passed through a cooling coil 37 into a storage tank 38.

Should excessive pressure be built up in the system, initial relief is afforded through a safety valve 39 in a line 40, leading from the top of the liquid cracking tower 25 to the bottom of the vaporizer, this valve being set for operation at approximately 25 pounds above the normal system pressure. A secondary relief is afforded through a valve 41 in a line 41', leading from the top of the vapor cracking tower to near the bottom of the vaporizer, this second relief valve being preferably set at approximately 50 pounds above the normal pressure. Consequently, should the relatively small line 30 leading from the vapor or final cracking tower to the secondary separator be insufficient to carry off the content of the system with sufficient rapidity and excessive pressure be built up, the relief means which I have provided will operate and prevent damage to the apparatus or interruption of the treating process.

The initial or liquid cracking tower may be relieved at any time through a line 42, leading to the cooling coil 37. The line 42 45 communicates with the tower through a line 43 leading from the bottom of the tower and provided with a hand valve 44; through a line 45 leading from the side of the tower, slightly above the bottom and provided with a hand valve 46 or through a line 47, leading to a higher elevation in the tower and provided with a hand valve 48.

While treatment of oil with my apparatus reduces accumulation of coke to a minimum, 105 there is, nevertheless, some accumulation in the cracking towers and it is for this reason that I provide for drawing off of the oil from the tower at different elevations, the lower outlet being employed when there is 110 a minimum accumulation in the tower and the upper outlets according to the depth of the coke. The second or vapor cracking tower may be drained into the line 42 through a branch 50, provided with a hand valve 51. 115 The expansion tower 13 may be drained through a line 52 and cooling coil 53 into a storage tank 54.

Should it be desirable to drain the still, as in the event of burning out a tube, the relief 120 may be effected through a line 55, connecting the line leading from the pump 21 to the still with the line 42 leading to the cooling coil 37. The line 55 is provided with a hand valve 56, which is normally closed but when opened, 125 will permit flow of liquid under the still pressure back through the cooling coil to rapidly relieve the still of the fluid and its pressure, the cooling coil reducing the temperature of the liquid so that by the time the latter reaches 130

the storage tank, it is below the flashing point, thereby obviating the danger incident to release of the oil into atmosphere under the usual still temperature.

5 The method of operation of recovering gasoline from crude oil described in connection with the description of apparatus contemplates the collection of the straight run and cracked gasoline in the same condenser. Should it be desirable to separate the straight run and the cracked gasoline, this may be effected by closing the valve 9 in the line 6 leading from line 5 to the vaporizer and conducting the vapors initially delivered to the 15 system through a line 57 into the top of the separator 11. The straight run gasoline vapors are then carried off through the line 12 to the condenser as originally described, the heavier components collecting as liquid in the 20 bottom of the separator and afterwards being drawn off through the charging still for cracking.

By a different mode of operation of the apparatus I separate the straight run and 25 cracked vapors by directing the cracked vapors into a separate condenser 58 connected with the line 10 through a branch 59 having a hand valve 60. For the operation of separately collecting the straight run and cracked 30 gasoline, the valve 9 in line 6 and a valve 61 in line 10 are closed, and the valve 62 in line 57 and valve 60 in line 59 are opened. When all of the gasoline is to be collected together, the valve 62 in line 57 and the valve 60 in 35 line 59 are closed, and valves 9 and 61 are opened to properly direct the flow.

It is desirable to maintain a proper volume of circulating fluid in the system at all times during operation of the apparatus. Should 40 the accumulation in the separator 11 fall below a desirable level, fresh crude oil may be supplied from a tank 63 connected with the pump 19 through a pipe 20 leading to pump 21 through a branch 64. The branch 64 is 45 normally closed by the ordinary tank valve (not shown).

As a modification of the mode of operation heretofore described, I provide additional 50 elimination of coke by passing the crude oil through the charging still at a higher temperature and pressure, such as 800 degrees F. and 100 pounds pressure, thereby eliminating all heavy fuel oils, cokes and tars, passing only gas oils and wax distillates to the extreme cracking zone. Under this mode of 55 operation the hot liquid under high pressure is passed initially to the secondary separator tower 31 through a line 65, provided with an automatic control valve 66 set to hold 60 the desired pressure in the still, the valves 9 and 62 in the line 5 and branch 57 being closed when the system is so operated. The liquid passing to the secondary separator tower separates into vapor and heavy liquid, 65 the vapors constituting approximately 85%

of the whole and passing out through pipe 35 into the vaporizer, the fuel oil from initial charging stock being drawn off from the secondary separator and fuel oil from the cracking zone being drawn off through the bottom 70 of the secondary separator and cooling coil into the tank 38. The vapors passing into the vaporizer are partially condensed, the lighter components passing on to the separator 11 where further condensation takes 75 place, the gasoline vapors eventually reaching the condenser, and liquid condensed in the separator 11 and in the vaporizer accumulating in the bottom of the separator and being pumped through the cracking still in 80 accordance with the operation first described.

When the apparatus is to be employed only for skimming or re-running of cracked distillates as when the cracking still is under repair or shut down for cleaning out, the 85 hand valve 67 in the line 35 leading from the secondary condenser to the vaporizer is closed and liquid from the charging tower delivered through the shower into the vaporizer, the vapors passing off to condensation and the heavier components back trapping in the bottom of the separator tower 11 and being drawn off through a back trap line 68 through a cooling coil 69 into a storage tank 70.

One advantage gained with my apparatus is that the non-condensable gases passing through the shower of charging stock are absorbed in the latter and recovered along with the condensable vapors, thereby saving a 100 great proportion of this useful component which would be lost if allowed to pass freely from the tower.

It is further apparent that with my apparatus, I effect the cracking in both liquid 105 and vapor phases at different stages in the run, the liquid phase being substantially confined to the first cracking tower and the vapor phase to the second tower.

I have not attempted to describe every 110 detail of structure embodied in the apparatus, such as gauges and the like, as this is ordinary equipment.

As a preferred construction I provide a spreader bed 71 in the vaporizer below the 115 shower nozzle 8, which may be supplied and emptied through a manhole 72, and provide a series of bubble plates 73 above the nozzle, each comprising upwardly directed necks 74 and heads 75 seated on the plates about the necks and having toothed lower edges 76 through which the vapors may pass to relief at the top of the tower.

While I have, during the description of the apparatus, mentioned specific temperatures 120 and pressures, I do not wish to be understood as limiting myself to them as any suitable temperatures and pressures may be employed.

It is apparent, therefore, that I have provided an apparatus whereby various treat-

ments of oils for the recovery of gasoline may be effected, the selection of modes of operation being optional, and with which the treatments described may be effected with 5 a material saving in labor and fuel costs.

What I claim and desire to secure by Letters Patent is:—

1. In apparatus of the character described, a charging still, a vaporizer, a line from the 10 charging still having an inlet to the vaporizer adjacent the upper end thereof, a cracking still, a cracking unit in receiving relation to the cracking still, a secondary separator in receiving relation to the cracking unit, means 15 for withdrawing condensates from the secondary separator, means for delivering vapor from the secondary separator to the vaporizer below said inlet from the charging still, a primary separator having a liquid outlet near its lower end, a vapor line leading 20 from the vaporizer above said inlet and delivering to the primary separator, a condenser in receiving relation to the primary separator, means for delivering liquid from 25 the vaporizer to the lower end portion of the primary separator, and means connected with said outlet for delivering liquid from the primary separator to the cracking still.
2. In apparatus of the character described, 30 a charging still, a vaporizer, a supply line from the charging still having an inlet to the vaporizer adjacent the upper end thereof, a cracking still, a cracking unit in receiving relation to the cracking still, a secondary separator 35 in receiving relation to the cracking unit, means for withdrawing condensates from the secondary separator, means for delivering vapor from the secondary separator to the vaporizer below said inlet from the charging still, a primary separator having an outlet 40 near its lower end and adapted to contain liquid at a level for sealing the outlet and an intake from the vaporizer above said liquid level, a vapor line leading from the vaporizer 45 above said inlet and delivering to the primary separator above the level of liquid therein, a condenser in receiving relation to the primary separator, means for delivering liquid from the vaporizer to the primary separator below 50 said intake, and means connected with said outlet for delivering liquid from the primary separator to the cracking still.
3. In apparatus of the character described, 55 a charging still, a vaporizer having an intake in its upper portion, a line leading from the charging still to said intake, a cracking still, a high pressure primary cracking tower for liquid phase cracking in receiving relation to the cracking still, a secondary cracking 60 tower for vapor phase cracking in receiving relation to the primary cracking tower and having a liquid outlet, a secondary separator, means for withdrawing condensates from the secondary separator, a line leading from the 65 secondary cracking tower to the secondary

separator, means for delivering vapors from the secondary separator to the vaporizer below the intake from the charging still, a primary separator having a vapor inlet in spaced relation with the bottom thereof to provide for a liquid level therein and having a liquid outlet and a valved drain port at its lower end, a vapor line leading from the vaporizer above said intake and adapted to deliver vapor to the vapor inlet of the primary separator, a liquid line for gravity flow of liquid from the vaporizer to the primary separator below said vapor inlet thereof, a line from said liquid outlet of the primary separator to the cracking still, and a condenser in receiving relation to the primary separator. 70 75 80

4. In hydrocarbon treating apparatus of the character described, a cracking still, a high pressure cracking unit in receiving relation to the cracking still, a secondary separator comprising a zone of low pressure in receiving relation to said cracking unit having an outlet for heavy hydrocarbons condensed therein, a vaporizer in receiving relation to the secondary separator, a primary separator 85 adapted to contain liquid at approximately a predetermined level, a condenser in receiving relation to the primary separator, means for delivering intermediate hydrocarbons condensed in said vaporizer to the primary separator to maintain the level of liquid therein, means for conducting vapor from the vaporizer and the primary separator, means for delivering liquid from the primary separator to the cracking still, and means connected 90 with said outlet for removing said heavy condensates from the secondary separator. 95 100

5. In hydrocarbon treating apparatus of the character described, a charging still, a cracking still, a vaporizer, a primary separator, a liquid line leading from the vaporizer to the primary separator, means for delivering liquid from the primary separator to the cracking still, a cracking unit in receiving relation to the cracking still, a secondary separator in receiving relation to the cracking unit and having a liquid outlet toward storage, a vapor line leading from the secondary separator to the vaporizer, a line for conducting streams from the charging still to the upper portion of the vaporizer whereby heated charging stock may be fed into the vaporizer to mingle with condensates of vapors from the secondary separator for flow to the primary separator to be delivered to the cracking still, and means for restricting the delivery means to recirculation of condensates comprising means for diverting the stream of charging stock from the charging still into the secondary separator for initial separation, and a manually controlled valve in the liquid outlet in the secondary separator adapted to be opened for conducting unvaporized portions of the charging stock toward storage. 110 115 120 125 130

6. In apparatus of the character described, a circuit, comprising a cracking still, a cracking unit in receiving relation to the cracking still, a secondary separator, a vapor line leading from the cracking unit to the secondary separator, a vaporizer, a vapor line leading from the secondary separator to the vaporizer, a primary separator, a liquid line for delivering condensates by gravity from the vaporizer to the primary separator, a vapor line leading from the upper portion of the vaporizer to the primary separator, and means for passing said condensates from the primary separator through the cracking still to the secondary separator, the primary separator having a vapor outlet, means for supplying charging stock in vaporous form comprising a charging still and a line leading from the charging still to the secondary separator, and means for conducting unvaporized portions of the charging stock from the secondary separator.

7. In apparatus of the character described, a circuit, comprising a cracking still, a cracking unit in receiving relation to the cracking still, a secondary separator, a vapor line leading from the cracking unit to the secondary separator, a vaporizer, a primary separator, a liquid line for delivering condensates by gravity from the vaporizer to the primary separator, a vapor line leading from the upper portion of the vaporizer to the primary separator, and means for passing said condensates from the primary separator through the cracking still to the secondary separator, a vapor line leading from the secondary separator to the vaporizer, a vapor outlet in the primary separator, means for supplying charging stock to the circuit comprising a charging still, a line leading from the charging still and having a branch to the upper portion of the vaporizer and a branch to the secondary separator, and means for selectively introducing liquid or vaporous charging stock to the circuit including manually operable valves in the branches and means for withdrawing unvaporized charging stock from the secondary separator when the vaporizer branch valve is closed to prevent flow of unseparated charging stock to the vaporizer and the other branch valve is open to admit charging stock to the secondary separator.

55 In testimony whereof I affix my signature.
EDWARD E. STEWART.
